UNITED STATES PATENT OFFICE.

MORITZ MARTIN, OF BITTERFIELD, PRUSSIA, GERMANY.

SAFETY-LIFT.

SPECIFICATION forming part of Letters Patent No. 271,884, dated February 6, 1883.

Application filed June 23, 1882. (No model.) Patented in Germany April 1, 1881, No. 18,387.

To all whom it may concern:

Be it known that I, MORITZ MARTIN, residing in Bitterfeld, in the Kingdom of Prussia, German Empire, have invented new and useful 5 Improvements in Safety - Lifts, (for which I have obtained Letters Patent in Germany, April 1, 1881, No. 18,387,) of which the following is a specification.

My invention relates to lifts such as are used 10 in factories and warehouses for raising and lowering goods and persons from one story to another; and the improvements consist in fitting to the openings through which the cage passes, under the arrangement and in the manner hereinafter described, movable guard-rails or fences, which are brought into their place and locked by the action of the cage whenever the latter leaves a floor, and which can be 15 opened only when the cage is in the opening. 20 In the accompanying drawings, Figure 1 is a transverse sectional elevation of a part of the lift, showing the guard-rail arrangement. Fig. 2 is a back view of the same; Fig. 3, a sectional plan on line $\alpha\alpha$, Figs. 1 and 2, with the 25 cage somewhat below the floor; and Fig. 4, a section on line yy of Fig. 3. Figs. 5 and 6 show a modified arrangement of the guard-rail mechanism.

The guard-rail, by which the opening in the 30 floor through which the lift passes is protected in front, is shown in Figs. 1 and 3. The same consists of a bar of iron, k , attached to or forming part of an axle, k' , which is mounted in the posts $f f'$, so as to be free to rotate 35 therein, while the bar or rail k reaches across the space between the posts f^2 and f^3 . To the rear end of the axle k' two arms, $u u'$, are so fixed as to be at right angles, or nearly so, to the rail k . The said rail, when let down, rests 40 with its free end in the bracket n .

m and l are tappets fixed to the cage, and adapted to strike against the arms u and u' , respectively, when these are in the position shown by dotted lines in Fig. 2 and the rail 45 k is in a vertical position.

o is a bolt, by which the rail is secured in its position when let down. This bolt is enclosed in the cross-bar v , and provided with a spring, p , arranged to push the same forward 50 and over the rail k . To the rear end of the

bolt o is fixed an arm, s , carrying a roller, t , which is acted upon by the inclines or cam-surfaces q and r , passing over into the straight back surface of the lift. When the lift is away from the floor the guard-rail k and the bolt o 55 are in the position shown by Figs. 3 and 4, (Fig. 3 of which represents the cage somewhat below the floor)—i. e., the bolt is projected forward over the end of the rail, thereby locking the latter and preventing it from being lifted. 60 Besides, the bolt is so arranged that it can only with difficulty be pushed back by hand. In rising from its position below the floor, the cage first of all acts with the cam-surface q on the roller t , (see Fig. 4, where these parts are 65 shown in dotted lines,) and pushes the bolt o back, so that the rail k may then be turned up by hand to make the passage to the platform of the cage free. By this turning the arms u and u' will be brought into horizontal position. (See 70 Fig. 2.) When the cage is to be lowered again the guard-rail may first be turned down by hand, if desired; but in case this is not done it will be tilted and turned down by the tappet m striking against the arm u . Thereafter 75 the cam-surface q leaves the roller t , thus setting the spring p free to push the bolt o forward again for relocking the guard-rail. When the cage is descending from a higher floor the 80 cam-surface r will cause the unlocking of the guard-rail. On the other hand, when the cage is to be raised to a higher floor, the guard-rail, if not previously turned down by the attendant, is tilted by the tappet l striking from below against the arm u' . The guard-rail is thus 85 always closed, and the bolt withdrawn or released automatically at the proper moment.

Below the bar k and parallel thereto one or more other bars may be arranged, which are pivoted to the post f^2 and connected to k by 90 links. By these bars, which will be lifted and let down together with the bar k , additional security is obtained in fencing in the opening in the floor.

When, in the construction described, the 95 guard-rail is tilted down automatically it will come down with considerable speed and strike rather forcibly on the bracket n . If this should be found objectionable, the modification represented by Fig. 5 in elevation and by Fig. 6 in plan 100

may be adopted. The tappet m in this case consists by preference of an inclined rib; but this form is not absolutely necessary. Opposite to m there is a rib or surface, m' , which, 5 however, must be inclined in order to act properly, and whose distance from m is slightly greater than the diameter of a lateral projection, u^2 , with which the arm u is provided. When, with this arrangement, the tappet m 10 has, by acting against the projection u^2 , tripped the guard-rail, the latter will not come down at once; but it will be lowered slowly on account of the projection u^2 leaning against the rib m' , which controls the motion of the guard-rail until the latter has attained the position 15 shown in dotted lines in Fig. 5, when it will be released and allowed to drop. The arrangement of the tappet l , the controlling-rib l' , and the projection u^3 on the arm u' are analogous 20 to the parts described, and therefore do not require any further explanation.

I claim as my invention—

1. The guard-rail k , turning on the axle k' ,

to which are fixed the arms u and u' , acted upon by the tappets m and l , attached to the 25 cage of the lift, all combined substantially as and for the purpose specified.

2. In combination with the guard-rail k , axle k' , arms u and u' , and tappets m and l , the controlling-surfaces m' and l' , and lateral projections u^2 and u^3 on the arms u and u' , respectively, co-operating therewith, as and for the purpose described.

3. In combination with the guard-rail k , axle k' , arms u and u' , and tappets m and l , the bolt 30 o , provided with spring p , and having an arm, s , carrying the roller t , which is acted upon by the cam-surfaces q and r , as specified, and for the purpose stated.

In testimony whereof I have signed my name 40 to this specification in the presence of two subscribing witnesses.

MORITZ MARTIN.
